(57) **CLAIM**

The ornamental design for a fender, as shown and described.

DESCRIPTION

FIG. 1 is a perspective view of a fender showing our new design.

FIG. 2 is a top plan view of the fender of FIG. 1;

FIG. 3 is a front view of the fender of FIG. 1; and,

FIG. 4 is a side view of the fender of FIG. 1.

The automobile and structure shown in broken lines throughout the drawing are for illustrative purposes only and form no part of the claimed design.
